DRIP PAN FOR A BARBECUE GRILL OR THE LIKE

Meredith J. Layman, 1361 Woodland Ave., Chico, Calif.

Filed Oct. 5, 1959, Ser. No. 57,817

Term of patent 14 years

(Cl. D81—10)

Fig. 1 is a top plan view of my new drip pan for a barbecue grill or the like;

Fig. 2 is a side elevation of same;

Fig. 3 is a bottom plan view;

Fig. 4 is an enlarged end view taken from the right of Figure 1;

Fig. 5 is a sectional view, partially broken away, taken substantially along the line 5—5 of Fig. 1.

I claim:

The ornamental design for a drip pan for a barbecue grill or the like, substantially as shown.
